UNITED STATES PATENT OFFICE

JOHN Q. SHUNK, OF BUCYRUS, OHIO

ROAD-GRADER BLADE

Application filed August 30, 1929. Serial No. 389,461.

My invention relates to a blade for road graders and the like, and one of the objects is to provide a blade in which less metal can be used than heretofore, at the same time increasing the efficiency of the blade.

A further object is to provide a blade in which the earth will slide along the blade with less resistance than with the blades heretofore used.

10 With these and other objects in view my invention consists in certain novel and peculiar features of construction and combination of parts as will be hereinafter more fully described and particularly pointed out in the 15 claims.

Referring to the drawing for a more complete disclosure of the invention:

Fig. 1 is an elevation showing the grader blade in relation to the mold board.

20 Fig. 2 is a vertical section of the grader blade.

The blade 1, made of rolled steel, is bolted to the mold board 2 by means of bolts 3. The mold board is supported from the frame 4 25 of the grader in the customary way, the brace 5 being connected at its upper end to the frame 4 and at its lower end to a bracket 7 secured to the back of the mold board.

The grader blade in its upper half 8 is 30 thinner than in its lower half 9. Grader blades are ordinarily about six inches high and of uniform thickness, running from about one-half to three quarters of an inch. I make my blade about one-eighth of an inch thinner 35 in the upper portion than in the lower portion.

The mold board is provided with an offset 40 10, and into this offset fits the upper thin portion 8 of the blade. The counter sunk hole 11 fits the head of the bolt 3.

In operation, the loose earth 12 does not pile up in front of the blade, but has a rolling motion. By having an offset on the face of the blade, as the dirt is scooped up, after 45 being raised a certain distance, it is loosened,

and the offset permits the earth to slide along the face of the blade and mold board with less resistance than if the blade was of the same thickness throughout its entire width. When the blade is otherwise worn out, the 50 upper or thinner section is of substantially the original thickness, due to the pressure of the earth being relieved on account of the offset.

Grader blades have heretofore been made of equal thickness throughout their entire 55 width. They are discarded when about three inches are worn from them, due to the fact that the upper half of the blade is bolted to the mold board in order to support it.

When the blade is worn up to the mold 60 board, the rest of the blade is discarded. By having the blade thinner in the upper part, a less amount of metal is discarded for the same effective scraping surface of the blade. Furthermore, the strength of the upper half 65 is greater than in a blade of uniform thickness equal to the thickness of the thinner portion. The wearing surface, or lower half, of a blade of a certain thickness can therefore be produced at less cost than where the 70 blade is of uniform thickness.

Heretofore, the cutting edge of grader blades has been made pointed and with a sharp bevel which wears away very quickly. By making the edge 13, in the beginning, 75 the same angle that it will ultimately wear to, the life of the blade is longer than heretofore.

I claim:

1. A grader blade made of a single plate 80 of metal, and having an upper portion adapted to be secured to a mold board, and a lower portion that acts as a scraper, and an offset on the front face of the blade between the said portions so that the upper portion is 85 thinner than the lower portion.

2. A grader blade made of a single plate 90 of metal, and having an upper portion adapted to be secured to a mold board, and a lower portion that acts as a scraper, and an offset

on the front face of the blade between the said portions so that the upper portion is thinner than the lower portion, the upper and lower portions being of substantially the same height.

3. A grader blade made of a single plate of metal comprising a lower portion having a flat wearing surface adapted to rest when in use upon the road surface, with a cutting edge at the front of the wearing surface, an upwardly extending plate portion having an offset on its front face that permits the earth to slide along the said face with less resistance above than below the offset.

15 In testimony whereof I affix my signature.
JOHN Q. SHUNK.
